UNITED STATES PATENT OFFICE.

FREDERICK WESTERMAN, OF CHICAGO, ILLINOIS.

DEPOSITING MACHINE.

1,290,444.

Specification of Letters Patent.

Patented Jan. 7, 1919.

Application filed May 22, 1918. Serial No. 235,929.

To all whom it may concern:

Be it known that I, FREDERICK WESTERMAN, a citizen of the United States, residing at Chicago, in the county of Cook and State of Illinois, have invented certain new and useful Improvements in Depositing Machines, of which I do declare the following to be a full, clear, and exact description, reference being had to the accompanying drawings, forming part of this specification.

The present invention has relation to that class of depositing machines more particularly designed to deposit confections upon the surfaces of rows of cakes that are advanced beneath a receptacle wherein such confections are contained, an example of this type of machine being shown in Letters Patent Nos. 1,121,430 and 1,121,431 granted to me December 15, 1914. More particularly my invention is directed to the improvement of the discharge nozzles for the confections and the valve mechanism whereby the delivery of the confections to the surfaces of the cakes is effected.

Figure 1 is a plan view of the die plate or carrier that extends beneath the receptacles for the confection and certain parts associated therewith. Fig. 2 is a view showing in side elevation the die plate or carrier and showing in vertical section the bar or receptacle above it and the carrier plate and table beneath it. Fig. 3 is a view on line 3-3 of Fig. 2, parts being shown in section. Fig. 4 is a view in vertical section on line 4-4 of Fig. 3. Fig. 5 is a view in horizontal section on line 5-5 of Fig. 6. Fig. 6 is a view in vertical section on line 6-6 of Fig. 2. Fig. 7 is a view in vertical section on line 7-7 of Fig. 6. Fig. 8 is a bottom plan view.

A designates the bottom casting of the confection receptacle which, as shown, is divided into compartments α and α' adapted to receive different confections, such for example, as fig paste in compartment α and icing in compartment α' . Longitudinally beneath the receptacle A extends the die carrier that is shown as formed of the plates or castings 10 and 11, these parts being suitably connected together as by screws 12. Through the ports or channels α^2 and α^3 that are formed in the plate 10 at opposite sides of the longitudinal division plate α^4 , material from the chambers α and α' will pass into the open spaces or chambers 15

and 16 that are formed partially in the plate or casting 10 and partially in the plate or casting 11 (see Fig. 6) on the opposite side of the division walls or diaphragms 17 that are held in suitable grooves (see Fig. 5) formed in the plates 10 and 11. The bottom of the plate or casting 11 is provided with the dovetail ribs 18 and 19 that serve to support the nozzles through which the confections will pass onto the cakes to be coated. As shown, the nozzles are formed by end plates or castings 20 (see Fig. 5) the edges of which are beveled to engage the lugs 19. Inclined plates 22 and 23 extend downwardly and inwardly from the ribs or lugs 18 and 19 and are connected to the end plates 20. Thus it will be seen that the nozzle beneath the chamber α is formed by the end plates 20, the inclined plate 22 and the division wall or diaphragm 17, while the nozzle beneath the chamber α' is formed by the end plates 20, the inclined plate 23 and the division wall or diaphragm 17. As shown more particularly in Fig. 5 of the drawings, the inner walls of the end plates 20 are provided with inwardly beveled portions 24 and with the inwardly extending vertical lugs 25 and 26.

On opposite sides of the wall or diaphragm 17 are arranged the valves or gates 30 and 31 that are formed with their seating portions inclined to seat against the lower portions of the inclined plates 22 and 23, these valves also performing the function of preventing the lodgment of material in the discharge orifices at the bottoms of the nozzles. The valve or gate 30 is held against the diaphragm 17 by the ribs 26, while the valve or gate 31 is held against the diaphragm 17 by the ribs 25. As shown, (see Figs. 6 and 7) each of the valves 30 and 31 is provided near its top with lugs 34 adapted to be engaged by the arms 35 projecting from the rock shafts 36 and 37. 100

By reference to Figs. 1 to 4 of the drawings, it will be seen that each of the rock shafts 36 and 37 is suitably journaled in bearings 38 at the ends of the plate 11 and each of these shafts is provided with a crank arm 39 whereby it may be actuated by suitable means, as for example, that shown in my beforementioned Letters Patent.

The cakes W to be coated with confections w may be advanced beneath the nozzles 110 above described, preferably by means of a carrier belt 45 supported upon a table 46.

The mechanism for supporting and moving the cakes and advancing them during the coating operation will preferably be of the character set forth in an application filed by me under date of April 12, 1918, Serial No. 228,255, but as such mechanism forms no part of the present invention, it need not be more particularly described herein, it being understood that this mechanism should be of such character that the rows of cakes will be advanced beneath the nozzles while the confection is being delivered therethrough onto the surfaces of the cakes.

In the preferred embodiment of my invention, the nozzle through which the fig paste or other confection that flows less freely than the icing with which it will be coated, may be shorter than the nozzle by which the icing or like coating confection will be discharged, as clearly shown in Fig. 6 of the drawings. The purpose of this construction is to enable the fig paste and icing to be more accurately or properly delivered onto the surface of the cakes. When the valves or gates 30 and 31 are raised to a position opposite that shown in Fig. 6, both the fig paste and the icing will flow onto the cakes beneath the nozzle as the cakes are being moved in the direction of the arrow Fig. 6 by the endless carrier belt 45, but as the icing flows more freely than the fig paste or thicker confection, it will reach the surface of the cakes slightly in advance of the stream of fig paste so that the end of the layer of fig paste may be completely covered by the icing. In practice, the valve 31 will be raised slightly in advance of the valve 30 to insure that the icing shall contact with the surface of the cakes slightly before the streams of fig paste reach the cakes, and after the rows of cakes W has been passed beneath the nozzles and the cakes have received their coating of confections, the valve or gate 30 will be closed slightly in advance of the closing of the valve 31. The precise relation of movement of the valves 30 and 31 may be varied, however, according to the character of the confections employed. A further advantage in extending the diaphragm 17 below the nozzle through which the icing will be discharged is that it serves to direct the flow of icing in a vertical direction and limit its spreading toward the center of the cakes and by having the nozzles for the icing terminate above the nozzles for the fig paste, the streams of icing when cut off by the valves 31 will better cover the ends of the layers of fig paste.

By reference more particularly to Figs. 5, 6 and 8 of the drawings, it will be seen that the discharge opening beneath the valve 30 is shorter than the discharge opening beneath the valve 31 that controls the flow of icing, the purpose of this being to permit of the film or layer of icing covering the side

edges of the layer of fig paste or like confection.

My invention affords an extremely simple and effective means whereby coatings of confections may be applied to the surfaces of cakes as they are moved beneath the nozzles in such manner as to give to the cakes a very uniform coating that contributes to their attractiveness and salability.

While I have described what I regard as the preferred embodiment of my invention, the details thereof may be varied without departing from the spirit of the invention and features of the invention may be employed without its adoption as an entirety.

Having thus described my invention, what I claim as new and desire to secure by Letters Patent is—

1. A depositing machine comprising chambers for containing confections to be deposited, discharge nozzles arranged side by side beneath said chambers and provided with valve mechanism, the discharge nozzles beneath one of said chambers extending below the discharge nozzles beneath the other of said chambers.

2. A depositing machine comprising a plurality of chambers for containing the confections to be deposited, discharge nozzles arranged side by side beneath each of said chambers and having contracted lower portions provided with discharge orifices, a vertically movable valve or gate within each of said discharge nozzles and adapted to pass into and close the orifice at the lower end of said nozzle, and means for reciprocating said valves or gates.

3. A depositing machine comprising a plurality of chambers for containing the confections to be deposited, discharge nozzles arranged side by side beneath each of said chambers having contracted lower portions provided with orifices, vertically movable valves or gates adapted to enter and close said orifices, and rock shafts for shifting said valves or gates.

4. A depositing machine comprising a plurality of chambers for containing confections to be deposited, discharge nozzles arranged side by side beneath said chambers and having parallel contracted portions provided with orifices, vertically movable valves or gates within said nozzles and adapted to close the orifices at the lower ends thereof, and rock shafts provided with arms for engaging said valves or gates to reciprocate the same in vertical direction.

5. A depositing machine comprising a plurality of chambers for containing confections to be deposited, discharge nozzles arranged beneath said chambers, said discharge nozzles having lower portions provided with orifices and having a single division wall separating the chambered portions of said nozzles, and vertically recipro-

cating gates or valves arranged within said nozzles, independent rock shafts for simultaneously actuating the valves or gates of each set of nozzles, and means for connecting said rock shafts with the upper ends of said valves or gates.

6. A depositing machine comprising a plurality of chambers for containing confections to be deposited, a plate extending beneath the bottoms of said chambers and provided with ports or channels through which the confections will pass, discharge nozzles arranged beneath said plate, a chambered support detachably connected to said plate and carrying said discharge nozzles, rock shafts extending from end to end of said plate, and valves or gates arranged within said nozzles and connected at their upper ends with said rock shafts.
7. A depositing machine comprising chambers for containing confections to be deposited, discharge nozzles arranged side by side beneath said chambers and provided with valve mechanism, said discharge nozzles having parallel orifices arranged in proximity,

the orifices of certain of said nozzles being longer than the orifices of others of said nozzles.

8. A depositing machine comprising chambers for containing confections to be deposited, discharge nozzles arranged side by side beneath said chambers and provided with valve mechanism, discharge nozzles for one of said chambers extending below the discharge nozzles for the other of said chambers, the orifices in the discharge nozzles for one of said chambers being longer than the orifices of the discharge nozzles for the other of said chambers.

9. A depositing machine comprising chambers for containing confections to be deposited, discharge nozzles arranged side by side beneath said chambers, said discharge nozzles having their adjacent or inner walls vertical and their outer walls inclined, valves having expanded lower ends to enter and close said orifices, and means for actuating said valves.

FREDERICK WESTERMAN.
